UNITED STATES PATENT OFFICE.

ROBERT ROTHENGATTER, OF NEW YORK, N. Y.

FOLDABLE KITCHEN-RACK.

941,653.

Specification of Letters Patent. Patented Nov. 30, 1909.

Application filed September 20, 1909. Serial No. 518,614.

To all whom it may concern:

Be it known that I, ROBERT ROTHENGATTER, a citizen of the United States, residing at New York city, Manhattan, county and State of New York, have invented new and useful Improvements in Foldable Kitchen-Racks, of which the following is a specification.

This invention relates to a foldable rack for supporting a number of pot lids or similar kitchen utensils in a reliable and convenient manner.

In the accompanying drawing: Figure 1 is a front view of my improved kitchen rack; Fig. 2 is a side view thereof; Fig. 3 a detail of part of the stem; Fig. 4 a cross section on line 4-4; Fig. 5; and Fig. 5 a perspective view of one of the clasps.

The rack comprises a stem carrying a series of spaced clasps which may be swung either downward to extend at an angle from the stem, or upward to fold against the stem.

The stem 10 is provided with a central longitudinal rib 11 flanked by flanges 12 and perforated transversely at suitable intervals as at 13. It may be attached in an upright position to a wall or other support by nails received within holes 14, or otherwise.

Each clasp is composed of a single piece of wire bent to form a transverse rear arm 15, a pair of end loops 16, upright front shanks 17, heels 18 and pintles 19. Shanks 17, cross arm 15 at a distance in front of the latter, so that an intervening gap 20 is formed. Heels 18 extend rearwardly from the lower ends of shanks 17, preferably at an acute angle, while pintles 19 project inwardly from heels 18.

The two pintles of each clasp are slipped

from opposite directions into one of the perforations from opposite directions into one of the perforations 13 of rib 11, so that the several clasps will be pivotally secured to the stem above one another. The co-relation of the parts is such that the two shanks 17 of each clasp straddle rib 11, while the two heels 18 thereof are aligned with flanges 12.

When the clasps are folded down, they will be sustained at the proper angle from stem 10 by the abutment of heels 18 against flanges 12, (Fig. 2). In this position the device is adapted for the reception of pot lids, etc., 21, which are slipped into the clasps between arms 15 and shanks 17. If the rack is out of use, or during transportation, the clasps are folded against stem 10, so that the device will occupy a minimum amount of space.

I claim:

1. A foldable kitchen rack comprising a stem, and a series of clasps composed of a rear transverse arm, a pair of end loops, a pair of upright front arms, a pair of heels extending from the front arms, and pintles on said heels that pivotally engage the stem.

2. In a foldable kitchen rack, a stem having a longitudinal rib, and flanges flanking said rib, combined with a series of clasps pivoted to the rib and having heels adapted to engage the flanges.

Signed by me at New York city, (Manhattan,) N. Y., this 18th day of September, 1909.

ROBERT ROTHENGATTER.
